(57) **CLAIM**

The ornamental design for a food container with handle, as shown and described.

DESCRIPTION

This application is related to co-pending U.S. application Ser. Nos. 29/520,688, 29/520,691, and 29/520,704, which are incorporated by reference herein.

FIG. 1 is a top, front and right side perspective view of a food container with handle showing my new design; FIG. 2 is a bottom, rear and left side perspective view thereof;

FIG. 3 is a top plan view thereof;

FIG. 4 is a bottom plan view thereof;

FIG. 5 is a front elevation view, the rear elevation being identical thereto;

FIG. 6 is a right side elevation view, the left side being identical thereto; and,

FIG. 7 is a cross-sectional view taken along line 7-7 of FIG. 3.
